UNITED STATES PATENT OFFICE.

JAMES K. P. PINE, OF TROY, NEW YORK, ASSIGNOR TO UNITED SHIRT AND COLLAR COMPANY, OF TROY, NEW YORK, A CORPORATION OF NEW YORK.

SHIRT.

1,137,081.

Specification of Letters Patent. Patented Apr. 27, 1915.

Application filed February 16, 1914. Serial No. 817,733.

To all whom it may concern:

Be it known that I, JAMES K. P. PINE, a citizen of the United States, and resident of Troy, Rensselaer county, New York, have 5 invented certain new and useful Improvements in Shirts, of which the following is a specification.

My invention relates to shirts of dress or negligee pattern, the skirts of which are cut 10 and seamed to form a pair of legs, so that a union garment is produced. Its object is to make the body portion of such garments readily adjustable both in length and girth. Other objects and advantages of the invention 15 will appear in this specification and be pointed out in the claims.

In the drawings, which represent a preferred form of my device, Figure 1 is a front; Fig. 2, a back view of the shirt as 20 worn; Fig. 3 is a partial rear view showing the shirt in open position.

11 designates the shirt, of which 12 is the front, and 13, the rear body portion. The front 12 has an opening 14 extending from 25 the collar band 15 to the crotch, and closed by a series of buttons and button-holes 16. At the rear, the body 13 is cut across, approximately at the waist line, leaving an opening 17 closable by a depending fall 18, 30 see Fig. 3. At each side of and above the opening 17 is provided a plurality of fastening devices, shown as a vertical series of buttons 19, three in number and closely adjacent to each other. The fall 18 is preferably strengthened by a band 20 at its upper edge, in which is cut at each end a plurality of coöperating fastening devices, shown as a horizontal series of button-holes 35 21, three in number also closely adjacent to each other. The leg portions 22 are formed by cutting and seaming the lower extensions of front 12 and back 13 in any desired manner.

The operation and advantages of the device 45 will be seen by reference to Figs. 2 and 3 of the drawings. Men who wear the same sized shirt may differ considerably in their body length, as well as in their desire to have the shirt drawn snugly at the crotch to 50 prevent rumpling of the bosom or front portion. This vertical adjustment of the shirt

body length is provided for by the substantially vertical series of buttons 19 at each end of the opening 17. At the same time, an adjustment of the girth at the waist line is 55 possible by reason of the substantially horizontal series of button-holes 21 in band 20. In other words, it will be seen that any one of button-holes 21 may be engaged with any one of buttons 19 at the same side of opening 17, and that, by means of this simultaneous vertical and horizontal adjustment in size, a more perfect fit may be gained and the wrinkling of the shirt front, either lengthwise or crosswise, may be prevented 60 or lessened.

It is evident that certain changes, *e. g.*, in the number of the fastening devices of either sort in either series, may be made in the device without departing from my invention.

What I claim is:

1. In a shirt of the class described, a rear opening; a fall for closing said opening; a closely adjacent series of fastening devices 75 at each side of said opening; a closely adjacent series of coöperating fastening devices at each free corner of said fall; said first named and said last named series being disposed in lines substantially at right angles 80 with each other.

2. In a shirt of the class described, a rear opening; a fall for closing said opening; a vertically disposed, closely adjacent series of fastening devices at each side of said opening; a horizontally disposed, closely adjacent series of coöperating fastening devices 85 at each free corner of said fall, substantially for the purposes set forth.

3. In a shirt of the class described, a rear 90 opening; a fall for closing said opening; a vertically disposed, closely adjacent series of fastening devices at each side of and at least in part above said opening; and a horizontally disposed, closely adjacent series of co- 95 operating fastening at each upper corner of said fall, substantially for the purposes set forth.

JAMES K. P. PINE.
